COMBINATION ADJUSTABLE BELT-SANDING MACHINE

Application filed August 16, 1926. Serial No. 129,403.

This invention relates to machines adapted to smooth wooden surfaces with an abrasive, or sanded, belt and especially to that class of such machine as is adapted for use in sanding irregular surfaces, ordinarily known as scroll sanding machines.

The objects of this invention are, first, to provide a machine which can be used as an ordinary flat surface sander, or can be changed to a spindle sander adapted to smooth any of a great number of irregular shapes; second, to provide a device which will enable such change to be made quickly, with but small additional cost over a machine adapted for flat surface work only; third, which can be applied to the present flat sanding machine in use, thus enabling a furniture or other manufacturer to enlarge the utility of his present machine without demanding additional floor space, or great expense; fourth, to provide various adjustable means whereby the position and attitude of the belt guide may be adjusted to bring the belt to the proper degree of tautness, to cause the belt to track correctly thereon, and to bring the guide into practical position whereby the article to be smoothed may be brought into contact therewith; and fifth, to provide a cheap, durable and efficient machine, which is easy to set up and convenient to use.

I attain these and other objects by the devices, mechanisms, and arrangements illustrated in the accompanying drawings, in which—

Fig. 1 is a front elevation of my complete machine as set up for use as an ordinary flat surface or table sander; Fig. 2 is a similar view, on a larger scale, of the idler end thereof; Fig. 3 is an end view of a portion of the part shown in Fig. 2; Fig. 4 is a plan view thereof; Fig. 5 is a perspective view, on a larger scale, of the brace holder head of the revoluble top thereof; Figs. 6, 7, and 8 show the details of the means for adjustably mounting the several spindle sander guides on the braces by which they are mounted on the machine, whereby the guide may be adjusted relative to the brace to cause the belt to track correctly thereon, Fig. 6 being a side elevation, Fig. 7 a longitudinal section, and Fig. 8 a

plan thereof; and Figs. 9, 10, 11, and 12 show various arrangements and shapes of the several spindle sander belt guides as mounted on the said brace-holder head of the machine. Similar numerals of reference refer to similar parts throughout the several views.

As shown in Fig. 1 the usual flat surface sander comprises a drive pulley 1, mounted on a suitable pedestal 2 and driven by a belt 3 from a motor 4, or by other means; an idler pulley 5, mounted on the opposite pedestal 6, in parallel arrangement and alinement with the pulley 1; a sand belt 7, having its abrasive surface outward, and running on the two said pulleys 1 and 5; a table 8, adapted to receive the article to be smoothed, and mounted on rollers 9 running, on the tracks 10, at right angles to the direction of motion of the said belt 7. The lower section of the belt 7 is pressed down by suitable manual means as it travels, on top of the article on the table 8.

In my improved machine I have changed the construction of the top of the second pedestal 6. This pedestal 6 is provided with the usual dovetail slot in its upper surface, and carries the plate 11, having a complementary dovetail lug 12 fitting in the said slot. The usual gear wheel 13, operated by the handle 14, engages suitable rack teeth cut in the said lug 12 whereby the plate 11 may be moved to adjust the distance away from the drive pulley 1 of the machine.

The plate 11 carries a vertical screw-threaded pin 15, extending upward from a central point, and the revoluble head 16 is mounted thereon. This head 16 rests on the said plate 11 and is clamped down thereon by means of the hand wheel or nut 17 which is screwed on the said pin 15. The position of the head 16 on the plate 11 and about the central axis of the pin 15, may be adjusted in order to bring the idler pulley 5 or other belt guide block into correct tracking position. This adjustment is obtained by means of a stop screw 18 passing horizontally through a short swingable arm 19 mounted on the fixed lug 20 on the side of the plate 11. The lug 19 may be swung down out of the path of the head 16 to permit it to pass thereover.

when desired, or may be swung up to permit used, thus bringing the adjustable axis of the
the said screw stop 18 to engage the side of the block or table at right-angles to that of the
the said head 16 and to hold it against displacement from such adjusted position by
5 the force applied thereto from the tension of
the sand belt 7.

The revoluble head 16 is provided on the
upper side of one end with a horizontal boss
21 in which a horizontal shaft 22 is secured.
10 This shaft 22 extends laterally from the said
boss and head 16 and carries the idler pulley
5 which is preferably mounted on roller bearings
on the said shaft 22. When the head 16
is swung into the position shown in Figs. 1-4
15 the idler pulley 5 is in line with the drive
pulley 1 and the sand belt 7 may be passed
over both of them and its tension adjusted by
moving the plate 11 and the head 16 by the
wheel 13, while the tracking of the said sand
20 belt 7 may be adjusted by the stop screw 18
engaging the side of the head 16. This ad-
justment is often needed because the sand belt
is made by gluing its ends together and there-
fore one edge may be slightly longer than the
25 other, or it may stretch slightly more than
the other under use. As soon as the adjust-
ment is made the head 16 is clamped in place
by screwing down the hand wheel 17 on the
pin 15. In this position the work table 8
30 may be used in the ordinary manner.

A vertical boss 23, having a vertical hole
24 therein, is also formed adjacent to the hori-
zontal boss 21, above described, and is adapted
35 to adjustably hold a supplementary guide
block, similar to that shown in Fig. 9 and
hereinafter described, whereby the two parts
of the said sand belt 7 may be separated by a
greater distance than the diameter of the idler
pulley 5, if desired.

40 The other end of the revoluble head 16 is
provided with a downward projecting lug 25
which is positioned substantially diametri-
cally opposite to the said boss 21. This lug
25 (Fig. 5) is provided with a plurality of
45 horizontal holes 26 and vertical holes 27,
therein. Each of these holes is provided
with a key 28 adapted to engage and clamp
the round brace bar, hereinafter described,
under the action of suitable set screws 29.

50 In Figs. 6 to 12, I have shown several dif-
ferent forms of sand belt guide blocks and
work rests or tables, adapted for use with
different kinds of work and each adjustable in
55 height and in distance from the drive pulley
by manipulation of their respective brace bars
in the said holes 26 or 27. These brace bars
or arms are of different forms and lengths,
according to the particular shape and posi-
60 tion of the belt guide block with which they
are to be used, a few only being illustrated
herein. In Fig. 9 two similar Z-shaped bars
or arms 30 are shown, thus bringing the ad-
justable axis of the blocks parallel with the
65 holes in the lug 25 in which they are mounted;
in Fig. 10 two right-angled arms 31 are being

used, thus bringing the adjustable axis of the
block or table at right-angles to that of the
holes in which they are secured; in Fig. 11
a U-shaped bar 32 is illustrated; and in Fig.
70 12 a Z-shaped bar 30 and a right-angled bar
31 are shown. It is readily seen from the
drawings that these bars or arms 30, 31 and
32 may each be adjusted axially and rotatably
in the holes 26 or 27 in which they may be
secured.

75 The connection between the several brace
bars 30, 31 or 32 with the respective belt
guide blocks is made adjustable around the
axis of the bar and also at an angle relatively
thereto, whereby the said belt guide block
80 may be turned and tipped in order to cause
the sand belt 7 to track properly thereon.
This adjustment is illustrated in detail in
Figs. 6, 7 and 8. The shank 33 of the par-
ticular brace bar is provided with a fixed
85 collar 34 at the point where it enters the
belt guide block. A slot 35 is made through
the belt guide block, said slot having parallel
sides but tapered edges (Figs. 6 and 7).
When the belt guide blocks are made of wood,
90 as is usual, I provide an entrance plate 36
through which the shank 33 passes and which
rests against the said collar 34. The other
end of the belt guide block is provided with a
plate 37 secured to it, through which the end
95 of the said shank 33 projects, and this plate
is provided with parallel guide shoulders 38.
A slide plate 39 is mounted between the
guide shoulders 38 and is provided with a
boss 40 through which the said end of the
100 shank 33 passes and in which it is secured by
the key 41 and the set screw 42, whereby it
is rotatably adjustable on the said shank 33.
The fixed plate 37 and the slide plate 39 each
have upward extending complementary lugs
105 43 through which the adjusting screw 44
passes. A keeper plate 45 may be secured
over the slide plate 39 to hold it between the
guide shoulders 38. Thus it will be seen that
110 by turning the screw 44 the angle between the
guide edge of the belt guide block and the
axis of the shank 33 of the respective brace
bar, may be adjusted as desired to cause the
sand belt 7 to track.

115 The several guide blocks, above referred
to, are preferably made of wood and may then
be covered with heavy canvas 54 (Fig. 7)
which is thoroughly impregnated with glue,
or made with any other suitable material.
The belt guide block 46, shown in Figs. 6,
120 8 and 11, is provided with two rounded ends
of different radii, each substantially a half-
circle, and joined by two flat surfaces of the
sides, all of which surfaces are adapted to
act as a backing for the belt 7 as it passes
125 thereover, and is adapted for smoothing small
curves, scrolls, "Queen Ann" legs, etc.; the
two belt guide blocks 47 (Fig. 9) may be
adjusted to occupy a great number of posi-
130 tions, in accordance with the convenience of

the operator, and are especially adapted for use with a narrow belt for smoothing a very wide range of irregular shapes, generally pressing the work against the belt itself between the two said blocks 47 without any backing; the large belt guide block 48 (Fig. 10) is provided with three flat surfaces, a fourth slightly convex surface, and with four corners of different degrees of sharpness. A work rest or table 49 may be used in connection with this block 48 and it may be supported on a similar brace bar or arm 31 on which it may be tipped and adjusted to occupy any desired vertical angle, thus greatly adding to its utility. In this case, as in the block 46, the work is pressed against the sand belt as it passes over the flat surface thereof, or over one of the curved or corner surfaces thereof. The belt guide block 50 (Fig. 12) is rotatably secured over the shank 33 of the brace arm 31 by a suitable set screw 51, whereby it may occupy any one of four positions, though usually either of two opposite positions are used. The main portion of this block 50 is cylindrical, except that a narrow flattened surface is provided (on its lower side in the position shown in Fig. 12) and this main part is provided with a rectangular head 52. This block is arranged to smooth inside or concave curves, irregular flats and rounds. The work rest or table 53 spans any side of this block and acts as a guide for the work and can be adjusted for any desired angle.

It will be observed, from Fig. 1, that this machine, when used as a scroll sander, is very convenient in that it permits the workman perfect freedom of his feet whereby he may stand as close to his work as he desires; also that the several adjustments of the plate 11, head 16, the brace bars 30—32, or the several belt guide blocks on said brace bars, are each independent of all the others and therefore any desired combination of adjustments can be quickly and easily made to bring the sand belt to the proper degree of tautness, to cause it to track properly, and to bring the working portion to the desired height for the workman operating the machine. It is also apparent that the machine can be quickly changed for one or another class of work with the least waste of time and with the least investment of capital and of space.

Having therefore described my invention, what I claim is:—

1. In a belt sanding machine, the combination of a driven abrasive belt; a pedestal; a head revolvably mounted on said pedestal and carrying in two diametrically opposite positions thereon two belt engaging devices, either of which may be brought into line to engage and support said abrasive belt; a removable stop mounted on said pedestal and adapted to removably engage said revolvable head, whereby said head may be held from

turning on said pedestal when one or the other of said belt engaging devices is in operation and whereby, when said stop is removed, said head may be turned to bring the other of said belt engaging devices into operative position. 70

2. A belt sanding machine as set forth in claim 1, wherein said removable stop is pivotally secured to said pedestal and is adapted to be moved into or out of position to engage 75 said revolvable head to hold it or to permit it to turn on the pedestal.

3. A belt sanding machine as set forth in claim 1, together with an adjustable screw, passing through said removable stop and 80 adapted to engage said revolvable head in adjusted position on said pedestal and to hold it from turning, whereby the belt is caused to track on the belt engaging device.

4. In a belt sanding machine, the combination of a pedestal with a head; a brace bar adjustably secured to said head and extending therefrom; a belt guide block loosely mounted on said brace bar; a plate secured to 90 said block; a second plate secured to said brace bar and slidably mounted on said first plate; and adjustable means securing said plates together in adjusted position, whereby the block is secured to the brace bar and may be adjusted thereon. 95

5. A belt sanding machine as set forth in claim 4, wherein said second or sliding plate may be secured to said brace bar in revolvably adjustable position thereon, whereby different portions of the block may be brought 100 under the belt engaged thereby.
